United States Patent Office

Des. 231,165

Patented Apr. 9, 1974

231,165

CHAIR

Henry Olko, Applegreen Drive,
Old Westbury, N.Y. 15568

Filed Jan. 11, 1972, Ser. No. 217,074

Term of patent 14 years

Int. Cl. D6—01

U.S. Cl. D6—57

Fig. 1

Fig. 2

Fig. 3

FIG. 1 is a perspective view of a chair embodying my design:

FIG. 2 is a reduced scale side view of the chair of FIG. 1, the opposite side being a mirror image of the side shown; and

FIG. 3 is a reduced scale plan view of the chair of FIG. 1.

I claim:

The ornamental design for a chair, as shown and described.
